UNITED STATES PATENT OFFICE.

WILLIAM J. EGGERS, OF NEW YORK, N. Y.

TANK-VALVE.

1,162,852.

Specification of Letters Patent. Patented Dec. 7, 1915.

Application filed April 2, 1915. Serial No. 18,664.

To all whom it may concern:

Be it known that I, WILLIAM J. EGGERS, a citizen of the United States, and a resident of the borough of Brooklyn of the city of New York, in the State of New York, have invented certain new and useful Improvements in Tank-Valves, of which the following is a specification, reference being had to the accompanying drawings, forming a part hereof.

This invention relates to ball valves of the character which are generally used to control the flow of liquids from a tank and which find especial usefulness in connection with flush tanks. Valves of this kind are generally formed wholly or partly of rubber, so that the valve will adapt itself automatically to its seat in the escape pipe and thereby insure a liquid tight closure. The greatest objection to these rubber ball valves has always been that they are subjected to great distortion which tends to give the ball a permanent set and thereby destroy its adaptability to uniform seating. Various schemes have been resorted to in an effort to counter-act the great distorting pressures to which such valves are subjected, by placing in the interior of the valve metallic reinforcements of diverse shapes, by making one hemisphere of the ball of metal, or by adopting numerous other expedients. These attempts, however, have not been entirely satisfactory, as in some cases the structures did not realize the ends aimed at, while in other instances the remedies suggested were prohibitive in cost and could not be incorporated in the valve during the manufacture thereof with such slight expense and permanency as are requisite for a device of this kind.

The present invention seeks to provide an inexpensive, simple, convenient and durable ball valve in which is embodied reliable means for preventing permanent distortion of the ball and for prolonging the life of the valve to an appreciable extent. These devices have been designed with especial reference to the condition of use surrounding a tank valve and to the manufacture thereof, to the end that they may be built in the valve during the manufacture thereof, without requiring the employment of any additional apparatus and without lengthening the time required for the usual molding and vulcanizing operations, and shall be susceptible of vulcanization with the body of

the valve in such manner as to constitute, in effect, an integral part thereof and insure a permanent union with the ball. These devices, in the present invention, take the form of a substantially conical piece of metal which conforms to the contour of the inner wall of one of the hemispheres of the ball and has united directly therewith, the usual metallic spud with which the lifting rod is engaged. This conical cap and the spud are vulcanized with one of the hemispheres and are incased by a separate envelop of rubber which is vulcanized with the said hemisphere and united therewith in such manner as to retain the conical cap and the spud permanently in place. In furtherance of the durability of the structure the cap may be formed with several apertures through which the rubber envelop may extend for union with the inner wall of the inclosing hemisphere. These apertures serve the additional function of venting the air between the surfaces of the metal cap and the walls of rubber incasing the same, thereby preventing the formation of blisters in the rubber during the molding and vulcanizing operations.

Another feature of the present invention resides in the formation of the upper surface of the ball valve of such contour as to minimize the pressure thereon and facilitate operation of the valve and insure the most effective results.

The invention will be described in greater detail with reference to the accompanying drawings in which is illustrated the preferred embodiment, and in which—

Figure 1 is a view in elevation of a tank valve constructed in accordance with the present invention. Fig. 2 is a view in vertical section taken through the valve shown in Fig. 1 on the plane indicated by the line 2—2 of Fig. 1 and looking in the direction of the arrows. Fig. 3 is a transverse sectional view taken through the valve shown in Fig. 1 on the plane indicated by the line 3—3 and looking in the direction of the arrows and showing particularly the finished interior of the upper hemisphere. Fig. 4 is a sectional view taken through the improved metallic cap and showing the spud engaged therewith.

For the purposes of this description, it will be convenient to describe first the structure of the improved valve as it appears in its finished state, and then point out, in connec-

tion with one method of constructing the valve, those features of the invention which make the valve inexpensive to manufacture, durable, and generally of a character to satisfy all requirements of a device of this character, both from the view point of the user and of the manufacturer.

The valve, indicated generally at a , as usual, is preferably formed throughout of two rubber sections a' and a^2 , united through a seamless, equatorial line of union a^3 , to constitute a homogeneous whole. The lower section a^2 is preferably formed as a true hemisphere, this contour having proven in use to be most satisfactory in effecting a water-tight closure between the valve and its seat in the escape pipe, under conditions where it is imperative that the yielding character of the valve be relied upon to effect such closure. In accordance with the present invention, however, the usual practice with respect to the upper section a' has been departed from, by forming this upper section, not as a true hemisphere, but as a conical cap, the area of which is appreciably less than would be the area of a true hemisphere formed on the same radius.

The means for reinforcing the improved valve and preventing such distortion thereof as would result in a permanent set comprise generally a metallic cap b of similar form to the inner surface of the conical section a' , which is adapted to be mounted snugly within the valve against the section a' and to be retained in position, by being vulcanized therewith, or by means of an inner sheathing of rubber c , or by both, as will appear more particularly hereinafter. The metal cap b carries at its apex a metallic spud d , of usual form into which may be threaded as usual, a suitable lifting rod (not illustrated) for the valve. Further, to enhance the permanency of union between the metal cap b and the upper section a' of the valve, the spud d may be of irregular outline, as suggested by the provision of the annular groove d' therein, to permit the rubber of the section a' to be pressed into intimate association with such irregularities during the molding operations. The disposition of the stiff metal cap b and its area, with respect to the upper rubber section a' of the valve a are such that the lifting force transmitted to the cap from the lifting rod through the spud d is uniformly distributed over the inner surface of the upper section and all tendency of the upper section to be distorted axially or otherwise is effectively counter-acted by the rigid cap b . Accordingly, such distortion of the valve as there is, occurs only where the distortion is required, that is, wholly in the lower hemisphere a^2 . This hemisphere yields freely under impressed force and adapts itself automatically to such forces so as to insure effec-

tive operation of the valve and proper seating thereof on the controlled escape pipe.

As has been noted briefly in the preamble, various attempts have hitherto been made to overcome the distorting pressures to which tank valves of the character illustrated are subjected; but many of these attempts, while more or less effective in attaining the results aimed at, have been impracticable in the art for the reason that they do not satisfy the requirements of commercial manufacture. The structure of the improved valve being now understood, the improved features thereof by which it becomes possible to embody the reinforcing devices directly in the valve during the course of manufacture thereof, without increasing materially the labor involved or the cost of manufacture, will now be considered. It is to be noted, however, that this invention is not to be limited in scope to any particular process of manufacture, but it will appear that the improved features, by reason of which the improved valve satisfies all of the requirements of commercial manufacturing, can be taken advantage of in other methods than that now to be described. In practice, it has been found convenient to employ the method of manufacturing rubber articles which is disclosed in a co-pending application of the present applicant filed on November 10, 1914, Ser. No. 871,234, to which reference is to be had for a complete understanding of the somewhat brief references now to be made. In accordance with this method of manufacture, the valve a is composed of two sections a' , a^2 , which are molded independently of each other from suitable blanks of raw or unvulcanized rubber, taken as it comes from the mill without calendering. The blank is then placed in a two-part mold, comprising male and female members, in which it is formed roughly into the required shape while subjected to moderate heat and pressure. This step of the method applies to the two sections a' and a^2 of the improved valve, except that when the blank out of which the conical section a' is to be molded is placed in its mold, the metal cap b is placed in the mold at the same time in proper relation to the inner surface of the blank. The molding operation of this section a' , under moderate heat and pressure, results in the partial embedding of the spud d in the rubber and a nominal union of the cap b with the inner surface of the conical section a' . At this point it is important to refer to the apertures b' with which the cap b is provided, these apertures b' serving, during the preliminary molding operation of the blank, to permit the air between the metal cap b and the conical section a' to be vented freely, thereby preventing the air from being trapped between the metal cap and the rubber and

causing blisters. These openings b' become of even greater importance during the second stage of the treatment of the upper section a' which will now be referred to.

- 5 After the blank has been molded into the generally conical form desired and the metal cap b has been nominally united therewith, in the manner described, the mold is opened and the thin rubber sheathing or envelop c 10 of rubber previously cut to proper form and size, is laid on the inner surface of the metal cap b and the section a' is replaced in the mold and further pressure and heat are applied in order that the sheathing c of rubber 15 may be pressed into proper shape and into intimate contact with the inner surface of the cap b and have its lower edges united nominally, as at c' , with the rubber in the section a' , thereby completely enveloping 20 the metal cap. During this step, this sheathing c may be pressed through the openings b' so as to unite nominally with the rubber in the section a' at the points where these openings are placed. During 25 this operation, however, these openings still serve as vents for the air so that no air is retained between the metal cap and the rubber walls in contact therewith. The two rough sections a' , a^2 , thus formed, are placed 30 together in a vulcanizing mold with their edges in contact and after being raised to the proper vulcanizing temperature are subjected to great internal pressure, as of a fluid, introduced under pressure through a 35 pipe which may be passed through the opening a^4 formed in the lower hemisphere a^2 . Under this great internal pressure, the rubber is pressed closely against the inner surface of the mold, the seam at the line of 40 union a^3 is obliterated, the cap b (which may be of brass or other suitable material) is vulcanized with the rubber in the section a' and with the rubber envelop c , and the union of the envelop with the rubber in the 45 section a' about the lower edges of the cap and through the openings b' is completed during the vulcanizing operation, so that all of the parts are united into a substantially homogeneous integral unit. This union is 50 further assisted by vulcanizing the spud d to the rubber about the apex of the conical section a' . During the course of manufacture, as noted, all of the air is expelled between the cap b and the rubber so that no blisters are formed at any part of the valve 55 and the exposed surface thereof is perfectly

smooth. The peculiar mechanical advantages of the valve having been pointed out particularly in connection with the description of the structure thereof, no further reference need be made thereto. 60

As indicated before, other methods in the manufacture of the improved valve may be employed and modifications in its structure be resorted to, but all such departures are 65 to be deemed within the spirit of this invention provided they fall within the scope of the appended claims.

I claim as my invention:

1. A flexible ball valve of rubber or the 70 like having a metallic plate secured on its inner surface, and a sheathing of rubber enveloping said plate and united with the rubber of the valve.

2. A flexible ball valve of rubber comprising a lower hemispherical section and an upper section, and having a metallic plate disposed throughout its surface in contact with the inner surface of the upper section, and a sheathing of rubber enveloping said 80 plate and united with the rubber of the upper section along the edge of the plate.

3. A flexible ball valve of rubber comprising a lower hemispherical section, an upper conical section united with the lower section, 85 and a conical metallic cap vulcanized to the inner surface of the upper section and carrying a spud for engagement with a lifting rod, and a sheathing of rubber enveloping said plate and vulcanized thereto and to the rubber of the upper section along the edge of the plate.

4. A flexible ball valve of rubber comprising a lower hemispherical section, an upper conical section united with the lower section, 95 and a perforated conical metallic cap vulcanized to the inner surface of the upper section and carrying a spud for engagement with the lifting rod, said spud being embedded in the rubber of the upper section 100 and vulcanized thereto, and a sheathing of rubber enveloping said plate and vulcanized thereto and to the rubber of the upper section along the edge of the plate and through the apertures therein.

This specification signed and witnessed this 31st day of March A. D. 1915.

WILLIAM J. EGGERS.
